UNITED STATES PATENT OFFICE.

JACOB F. ARNOLD, OF BELLEVUE, OHIO.

TABLE.

1,308,652.

Specification of Letters Patent.

Patented July 1, 1919.

Application filed December 15, 1916. Serial No. 137,258.

To all whom it may concern:

Be it known that I, JACOB F. ARNOLD, a citizen of the United States, residing at Bellevue, in the county of Huron and State 5 of Ohio, have invented certain new and useful Improvements in Tables, of which the following is a specification.

The invention relates to tables of the type generally known as desk tables and 10 usually having a flat top, a center drawer, and book racks or cases at its opposite ends; and the general object of the improvement is to combine in a single article of manufacture all of the advantageous features of 15 a library table, a writing desk, and dust proof book cases.

The object of the invention thus generally stated is attained by mounting in the drawer, in compact arrangement, a receptacle or 20 holder for writing materials and a desk leaf of ample size for use as a writing table or support, the holder for the writing materials being operable either automatically or manually from a normally reclined or 25 inoperative position to an upright or operative position when the drawer is opened and provided with means for maintaining it in such position; and by providing book compartments at the opposite ends of the table 30 which are adapted to be completely closed against the entrance of dust or dirt by 35 swinging doors having a sliding pivotal mounting whereby they are adapted to be slid edgewise into inoperative position in the compartments.

The construction and arrangement by 40 which the general objects and purposes of the improvement set forth are attained, together with other and ancillary advantages, 45 are illustrated in the accompanying drawings forming part hereof, in which—

Figure 1 is a perspective view of a table showing the drawer opened and having a 50 holder for writing materials in operative position therein, and one of the book compartments with its door opened;

Fig. 2, a sectional view through the table on line 2—2, Fig. 1, showing the drawer closed with the holder in inoperative position, and automatic operating means;

Fig. 3, a fragmentary sectional view on line 3—3, Fig. 1, showing the holder main-

tained in upright position by the operating means;

Fig. 4, a fragmentary perspective view 55 showing the pivotal mounting of the book compartment door, the door being shown in section;

Fig. 5, a central sectional view through a table showing the drawer closed and having 60 a slightly different form of holder therein, the operating means for the holder being omitted;

Fig. 6, a fragmentary top plan view showing a holder held in upright operative position in the drawer by a sliding cover for 65 the writing instrument container, engaging one of the upper side edges of the drawer;

Fig. 7, a sectional view on line 7—7, Fig. 6;

Fig. 8, a sectional view through the table 70 with the drawer closed and showing another form of holder;

Fig. 9, a fragmentary sectional view on line 9—9, Fig. 8, but showing the holder 75 locked in upright position;

Fig. 10, a fragmentary perspective view showing the locking means for the holder; and

Fig. 11, a similar view showing a detach- 80 able pivotal mounting for the holder.

Similar numerals refer to similar parts throughout the drawings.

The table includes the usual top 1 supported by the legs 2 suitably braced, the 85 center drawer 3, and book compartments 4 at the opposite ends of the table at each side of the drawer.

The drawer 3 which may be of any well known or preferred construction, and slid- 90 ably supported in the table, is provided with a desk leaf 5 hingedly mounted in the drawer near and preferably slightly rearward of its center. Preferably the desk leaf is of the same width as the drawer except 95 that at its rear or hinged edge, its end edges are notched as at 6 to permit it to be entered between the side walls of the drawer to which it is pivoted by means of pivot pins 7; and the upper edges of the 100 side walls of the drawer are cut away as at 8 to permit the upper surface of the leaf, when swung downwardly thereon, to lie flush with the upper edges of the drawer.

Near its rearward right hand corner the desk leaf may be provided with an opening 10 to permit access to an ink well positioned beneath it in the drawer below, and 5 a transverse partition 3^a is provided in the drawer at the hinged end of the desk leaf, to form a separate compartment in the forward portion of the drawer.

In the rear portion of the drawer 3, means 10 are provided for holding writing materials such as stationery, writing instruments and the like, in compact and orderly arrangement, consisting of a rack or holder 11 pivotally mounted for operation from a normally reclined position when the drawer is 15 closed to an upright position when the drawer is opened. The holder, which for convenience will be described with reference to its normal inoperative position, 20 is made substantially rectangular in shape with upper and lower walls 12 and 13, side walls 14 and rear or bottom wall 15, and is of a length adapted to fit between the side walls of the drawer by which it is pivotally 25 supported on an axis slightly above its center of gravity so that it will normally be suspended in reclined position, with its upper wall substantially flush with the upper edges of the drawer. On its interior, 30 the receptacle is provided with a plurality of longitudinal and transverse partitions or divisions 16 to form receptacles for paper, envelopes and the like, and on its lower wall with a container 17 for writing instruments, normally opening forwardly and provided with a cover 18. The forward end 35 of the holder is preferably shaped so that the open ends of the various receptacles will lie in a forwardly declined plane when the holder is in operative position, in order that 40 they will be readily accessible.

A detachable pivotal mounting, shown most clearly in Fig. 11, is preferably provided for the holder at each side of the 45 drawer, consisting of a pair of laterally yielding metallic supports or arms 19 mounted uprightly on the inner surfaces of the drawer side walls and having bearing openings 20 in their upper ends adapted to receive pivot pins 21 carried by pivot plates 22 which are secured in their proper position on the side walls of the holder. The upper ends of the arms are bent away from the side walls of the drawer so that they yieldingly 50 maintain the pivot pins 21 in the bearing openings. It will thus be evident that the holder may be readily detached from the drawer by springing the arms outwardly out of engagement with the pivots; and that 55 the pivotal bearings form a transverse axis of rotation passing through a median portion of the body of the receptacle, upon which axis the same may be bodily rotated.

Means may be provided for automatically 60 rotating or tilting the holder from its nor-

mally reclined or inoperative position into upright position, when the drawer is opened for use, and maintaining it in such position, as shown in Figs. 1, 2 and 3; or such means may be omitted and the holder manually 70 operated into operative position and means provided for holding it in such position, as shown in Figs. 5 to 9.

The means for automatically tilting the holder into operative position, preferably 75 consists of a block or bar 23 mounted transversely on the upper wall of the holder slightly rearward of the pivot pins 21 and the upper rail 24 of the table frame forming a cam abutment for the block, the block 80 being adapted to engage the rail when the drawer is opened. The upper forward edge of the tilting bar 23 and the lower rearward edge of the rail 24 are shaped to form coacting cam surfaces 23^a and 24^a, on the bar 85 and rail respectively, whereby when the bar engages with the rail in the forward movement of the drawer, the bar is first caused to ride downwardly to rotate the holder into upright position and then forwardly into 90 engagement with the lower side of the rail to maintain the holder in operative position.

One or more stops 25 of any suitable shape are provided at the rear end of the drawer, 95 which stops project below the bottom wall thereof and are adapted to engage with the inner side of the lower rail 26 of the table frame when the holder has been tilted, thus preventing the drawer from being drawn forwardly far enough to disengage the tilting block from the rail.

The instrument container 17 is so positioned on the lower wall of the holder that when the holder is rotated into upright position, the forward portion of the container 100 105 will protrude slightly above the side edges of the drawer so that the cover 18, which may be slidably mounted in dove-tailed grooves in the container, may be slid to one side in opening the container.

As shown in Fig. 3, the automatic tilting means serve to rotate the holder only to a partial upright position, so that the container 17 is fixed on the lower wall of the holder at an acute angle therewith whereby 110 when the holder is at the upper limit of its movement the container will open directly upwardly; and when the automatic tilting means are omitted as in Figs. 5 to 9, the holder is adapted to be manually rotated to 115 a full upright position, so that in this instance the container 17 is secured on the lower wall of the holder at right angles therewith. In either case, the cover 18 may be utilized to maintain the holder in upright 120 position by sliding the same endwise so that it will engage with the adjacent upper edge of the side wall of the drawer, as shown in 125 Figs. 1 and 6.

When the container is mounted on the 130

holder at an acute angle therewith, the lower rear edge thereof may be beveled as at 17^a to prevent an interference with the bottom of the drawer, but when the container is 5 mounted at right angles with the lower wall of the holder, it may be necessary to remove the bottom of the drawer below the holder in case the depth of the drawer is not sufficient to permit its free rotation.

10 As shown in Figs. 9 and 11, means may be provided at one or both sides of the drawer for automatically locking the holder in upright position. For this purpose the side walls of the holder are enlarged, as shown 15 in Fig. 8, to include between them the container 17 on the lower wall of the holder; and a spring latch 26, having its free upper or forward end bent outwardly to form a catch 26^a and then upwardly, is secured at 20 its lower or rear end to the side wall of the holder at a point below the container 17. The free end of the latch is bent outwardly away from the side wall of the holder and yieldingly engages with the side wall of the 25 drawer when the holder is in inoperative position, and is of such length that when the holder is rotated into upright position, it will spring outwardly so that the catch 26^a will engage with the upper edge of the side 30 wall of the drawer and maintain the drawer in operative position.

The cover 18 for the container 17 in this instance is suitably hinged to the lower wall 35 of the holder, and in order to lock it in closed position when the holder is in inoperative position, a pin 27 is provided on the upper free end of the latch which extends inwardly at substantially right angles therewith, and when the latch is pressed inwardly 40 to release it from operative position, the pin is adapted to enter through an opening 28 in the wall of the holder into an opening 29 in the end of the cover 18, in which position it is held until the holder is again rotated into 45 upright position.

It will thus be evident that simultaneously with the releasing of the holder from its upright position by pressing the locking latch inwardly, the cover for the container is 50 locked against rotation and is held in such position by the side walls of the drawer.

The book compartments 4 at each end of the table are formed by means of bottom, side and rear walls, immediately below the 55 top 1 which serves as a top wall, and are closed against the entrance of dust and dirt by means of swinging doors 30 which are pivotally mounted at the upper ends of the compartments and adapted to slide edgewise 60 into inoperative position therein. As shown in Fig. 4, each compartment is provided along the upper inner edges of its end walls with a slideway by which the door is supported. Such slideway consists of an angular bar 32, the upright portion of which is

secured to the side wall of the compartment between the inner wall of the leg 2 of the table and the rear wall of the compartment, and slightly below the top wall, and is provided with a longitudinal groove 33 in 70 which a dowel pin 34 mounted in the end of the door near its upper edge is adapted to slide. The horizontal portion of the bar forms a track 35 which serves to support the door as it slides into and out of the compartment, and at its forward end is rounded downwardly to form a cam abutment 36 with which the inner side of the door engages near its hinged edge to prevent it from sliding inwardly at its upper end when closed, 80 the groove 33 being continued outwardly beyond the end of the bar into the leg of the table in order to permit a swinging operation of the door.

I claim:—

1. A table having a desk drawer supported for sliding forward and rearward therein, and a forwardly opening receptacle for writing material and the like supported in the drawer for rotating upon a transverse 90 axis passing through a median portion of its body, the forward open end of the receptacle being rotated downward to an inaccessible position when the drawer is closed and upward to an accessible position when the 95 drawer is opened.

2. A table having a desk drawer supported for sliding forward and rearward therein, a forwardly opening receptacle for writing material and the like, supported in the 100 drawer for rotating upon a transverse axis passing through a median portion of its body, the forward open end of the receptacle being rotated downward to an inaccessible position when the drawer is closed, and 105 means actuated by the forward movement of the drawer for rotating the forward end of the receptacle upward into accessible position when the drawer is opened.

3. A table having a desk drawer supported 110 for sliding forward and rearward therein, a forwardly opening writing material receptacle supported in the drawer for rotating upon a transverse axis passing through a median portion of its body, the receptacle being 115 rotated downward to an inaccessible position when the drawer is closed, and upward to an accessible position when the drawer is opened, and means for stopping the holder in accessible position.

4. A drawer for tables or the like having a holder for writing materials rotatably mounted therein, and a spring latch secured to the holder having a catch on its free end adapted to engage with the upper edge of 125 the side wall of the drawer to lock the holder in operative position.

5. A drawer for tables or the like having a holder for writing materials rotatably mounted therein, including a container for 130

writing instruments having a cover, and means engaging the cover for locking it in closed position when the holder is in inoperative position, and disengaged therefrom when the holder is in operative position.

6. A drawer for tables or the like having a holder for writing materials rotatably mounted therein, including a container for

writing instruments having a cover with an opening in its end, a spring latch bent outwardly and upwardly at its free end and having a pin thereon entered into the opening in the cover when the holder is in inoperative position and disengaged therefrom when the holder is in operative position.

JACOB E. ARNOLD.
